UNITED STATES PATENT OFFICE.

ELIZABETH EDMONSTON, OF NEWBURG, NEW YORK.

DESIGN FOR A PICTURE-FRAME.

SPECIFICATION forming part of Design No. 18,501, dated August 7, 1888.

Application filed June 25, 1888. Serial No. 278,153. Term of patent 7 years.

To all whom it may concern:

Be it known that I, ELIZABETH EDMONSTON, a citizen of the United States, residing at Newburg, in the county of Orange and State 5 of New York, have invented a certain new and useful Design for Picture-Frames; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

The invention relates to a new and original 15 design for picture-frames; and it consists in the novel design, as hereinafter described.

Figure 1 of the drawings represents my design and is a front view thereof, and Fig. 2 is an end view.

20 The leading feature of my design consists in the representation of an open book, in the cen-

ter of which is the picture-space A. The central longitudinal portion, B, is depressed to represent the joined or bound edge of the opposite leaves, and from the central line the 25 face may be transversely convexed and concaved, as at C. The four edges have parallel lines or grooves to indicate the separation of the leaves. The inwardly-turned edges E indicate the irregular or ragged edge of a binding, and a corner of a leaf is folded over or dog eared, as at F.

What I claim is—

The design for a picture-frame, substantially as herein shown and described.

In testimony whereof I affix my signature in presence of two witnesses.

ELIZABETH EDMONSTON.

Witnesses:

C. L. WARING,
E. L. STODDARD.
